UNITED STATES PATENT OFFICE.

GUSTAV L. JAEGER, OF NEW YORK, N. Y.

BOX-STAYING MACHINE.

SPECIFICATION forming part of Letters Patent No. 410,522, dated September 3, 1889.

Application filed May 1, 1889. Serial No. 309,257. (No model.)

To all whom it may concern:

Be it known that I, GUSTAV L. JAEGER, a citizen of the United States, residing at New York, in the county and State of New York, 5 have invented new and useful Improvements in Box-Staying Machines, of which the following is a specification.

This invention relates to an improvement in box-staying machines, and by means of 10 this invention the stay will be pressed with equal firmness against two sides or faces of the box, as set forth in the following specification and claims, and illustrated in the accompanying drawings, in which—

15 Figure 1 is a front elevation, partly in section, of a box-staying device. Fig. 2 is an inverted plan view of an anvil. Fig. 3 is a plan view of a base for an anvil. Fig. 4 is a side elevation of a modification. Fig. 5 is a 20 side elevation, partly in section, of an anvil. Fig. 6 is a section along line xx , Fig. 1. Figs. 7 and 8 show a modification.

Similar letters indicate corresponding parts.

In the drawings, the letter A indicates a 25 plunger or die adapted to press a staying-strip B about a box-corner. The plunger is operated by suitable mechanism, (not shown,) such as a cam, foot-lever, or other appliance. The box is made to rest on the anvil or support C. Said anvil is carried by a suitable 30 arm or base D. The anvil is made laterally movable upon its base, so that in case of unevenness in the box-sides—as, for example, in Fig. 1, where one box-side is composed of 35 a single wall E, while another box-side is partly composed of a double wall E—the anvil can move laterally to such position that the plunger A can press the stay B with equal firmness against said two box-sides.

40 The lateral movability of the anvil is secured in any suitable way. In Figs. 1 to 3 the lateral movability of the anvil is obtained by a pin-and-slot connection, the pins F and slots G allowing the anvil to move laterally, while preventing the anvil falling off the arms D. In Fig. 4 the pin-and-slot connection is replaced by dovetails F, which engage suitable lateral ways G.

When the anvil is relieved from pressure, a spring H returns said anvil to the starting 50 position. By having the under face of the anvil rounded the anvil can rock on its base, thus enabling said anvil to assume a position adapted to secure a firm pressure evenly about the box-corner. The anvil can be thus 55 rounded both transversely, Fig. 1, as also longitudinally, Figs. 5 and 6.

The spring H is shown suitably secured to the base by a screw I and engaging a suitable eye or depression K in the anvil. 60

In place of the anvil being made laterally movable, it is obvious that the die can be made laterally movable, thus again securing an even pressure about the box-corner. In Fig. 7 is shown a face view of a laterally- 65 movable die A, held in place by a dovetail connection F G. A spring H tends to hold the die A in the starting position on its support. Fig. 8 is a side view of Fig. 7. When the die A is laterally movable, as in Figs. 7 70 and 8, the anvil C may be fixed.

What I claim as new, and desire to secure by Letters Patent, is—

1. In a machine for applying corner-stays to boxes, the combination, with the die A, of 75 an anvil or support C, said anvil being made laterally movable upon its base, substantially as described.

2. In a machine for applying corner-stays to boxes, the combination, with the die A, of 80 an anvil or support C, having a laterally-oscillating motion, substantially as described.

3. In a machine for applying corner-stays to boxes, the combination, with the die A, of 85 an anvil or support C, having a longitudinally-oscillating motion, substantially as described.

4. In a machine for applying corner-stays to boxes, the combination, with the die A, of 90 an anvil or support C, laterally movable upon its base, and a spring H, for holding said anvil in the starting position, substantially as described.

5. In a machine for applying corner-stays to boxes, the combination, with the die A, of 95 an anvil or support C, made laterally movable

upon its base and secured to said base by a pin-and-slot connection, substantially as described.

6. In a machine for attaching corner-stays to boxes, the combination, with the die A, of an anvil or support C, either said die or anvil being made laterally movable, substantially as described.

In testimony whereof I have hereunto set my hand in the presence of two subscribing witnesses.

GUSTAV L. JAEGER.
